UNITED STATES PATENT OFFICE

HARRIET FORDYCE, OF ST. LOUIS, MISSOURI

DESIGN FOR A RECEPTACLE

Application filed January 17, 1929. Serial No. 29,660. Term of patent 7 years.

To all whom it may concern:

Be it known that I, HARRIET FORDYCE, a citizen of the United States of America, residing in the city of St. Louis, in the State of Missouri, have invented a new, original, and ornamental Design for a Receptacle, of which the following is a specification, reference being had to the accompanying drawing, forming a part thereof.

The drawing is a perspective view of a receptacle, showing my new design.

I claim:

The ornamental design for a receptacle, as shown.

HARRIET FORDYCE.
